UNITED STATES PATENT OFFICE.

HORACE FIELD PARSHALL, OF LONDON, ENGLAND.

AUTOMATIC MAXIMUM-SPEED GOVERNOR FOR ELECTRICALLY-PROPELLED VEHICLES.

SPECIFICATION forming part of Letters Patent No. 658,117, dated September 18, 1900.

Application filed June 12, 1897. Serial No. 640,521. (No model.)

To all whom it may concern:

Be it known that I, HORACE FIELD PARSHALL, a citizen of the United States of America, residing at 83 Cannon street, in the city 5 of London, England, have invented certain new and useful Improvements in Automatic Speed-Governors, (for which I have obtained a patent in Great Britain, No. 17,666, dated August 10, 1896,) of which the following is a 10 specification.

The object of my invention is to provide an efficient and reliable speed-governor for electric motors.

My improvements are particularly useful 15 in connection with electric motors used to drive vehicles and in that application act to prevent the speed of the vehicles from exceeding a certain predetermined maximum.

My invention contemplates the use of a circuit-breaker capable of opening or modifying 20 the motor-circuit with electrically-operated means for actuating the circuit-breaker in response to changes of speed of the motor.

The nature of my invention will be more 25 specifically pointed out in the following specification and its scope indicated in the annexed claims.

In the drawings attached to this specification, Figure 1 is a diagrammatic representation 30 of a device embodying my invention, and Fig. 2 is a similar representation of a modified form.

Referring to Fig. 1, A is the shaft of the motor, and B is a circuit-breaker inserted in 35 series with the motor-armature. This circuit-breaker is here shown as constructed in a well-known manner in accordance with United States Patent No. 558,518 to William B. Potter, though it will be apparent that my invention 40 may be adapted to various other forms of circuit-breakers. In the particular form illustrated the circuit-breaker comprises a switch B', with an auxiliary switch B² in multiple therewith controlled by a handle H through 45 a toggle T. The spring tends continuously to open the circuit first at B' and then at B²; but this tendency is withstood by the action of the latch L, controlled by a spring l. When the current in the coil C rises to a certain pre- 50 determined amount, the latch L is attracted downward and the spring l is allowed to withdraw the brush B' from the contacts. This

causes current to flow through the magnet-coil m' m², so that by the time the final arc is formed at the contacts B² a field exists of sufficient strength to extinguish it. 55

In carrying out my present invention I provide a tripping-coil C' upon the circuit-breaker, acting upon the armature p and tending when energized to draw down the latch L 60 and allow the spring l to open the circuit. This coil is connected in series with an auxiliary source of electromotive force, here shown as a battery B', through the stationary contacts b b and the movable contact d'. This 65 movable contact is actuated through the lever D by the governor G, which is in some manner run at a speed corresponding to the speed of the motor. If the speed of the motor rises too high, the contact d' is closed and the coil 70 c' is caused to trip the circuit-breaker B.

In the form shown in Fig. 2 I provide as an auxiliary source of electromotive force a generator G', which is mounted on the shaft of the motor A or is in any other way driven at 75 a speed corresponding to the speed of the said motor. This generator is connected directly in series with the auxiliary tripping-coil C'. Whenever the speed of the motor rises above a certain point, the electromotive force generated by the auxiliary generator G' becomes sufficient to cause the auxiliary tripping-coil to act, and thus opens the circuit of the motor. 80

It will be evident that with either of the forms shown it is impossible for the attendant to close the circuit-breaker in such a way that it will remain closed until the speed of the motor or of the apparatus driven by the motor has been reduced to the proper value. 85

What I claim as new, and desire to secure 90 by Letters Patent of the United States, is—

1. In combination, a line-circuit, a motor supplied thereby, a circuit-breaker controlling the current flowing to said motor, an auxiliary source of electromotive force, and means 95 for actuating such circuit-breaker by current from the auxiliary source when the motor speed rises too high.

2. In combination, a line-wire, a dynamo-electric machine, a circuit-breaker in the line, 100 an auxiliary dynamo connected to said machine, and a coil on the circuit-breaker in circuit with the auxiliary dynamo.

3. The combination with a dynamo-electric

machine, of a circuit-breaker, a source of electromotive force proportional to the speed of said machines, and a coil upon the circuit-breaker supplied with current from the said

5 source.

4. The combination with a motor, of a circuit-breaker containing a series coil and an auxiliary coil, and means for causing the auxiliary coil to open the circuit-breaker when

10 the speed of the motor rises too high.

5. The combination with a dynamo-electric

machine, of a circuit-breaker containing a series coil and an auxiliary coil, and means for causing the auxiliary coil to open the circuit-breaker when the machine departs too much 15 from normal speed.

In witness whereof I have hereunto set my hand in presence of two witnesses.

HORACE FIELD PARSHALL.
